UNITED STATES PATENT OFFICE.

LEO L. PFEIFER, OF COLUMBUS, OHIO, ASSIGNOR TO THE JNO. W. BROWN MANUFACTURING CO., OF COLUMBUS, OHIO, A CORPORATION OF OHIO.

BUFFING AND POLISHING MACHINE.

1,246,996.

Specification of Letters Patent. Patented Nov. 20, 1917.

Application filed August 16, 1916. Serial No. 115,119.

To all whom it may concern:

Be it known that I, LEO L. PFEIFER, a citizen of the United States, residing at Columbus, in the county of Franklin and State of Ohio, have invented certain new and useful Improvements in Buffing or Polishing Machines, of which the following is a specification.

This invention relates to buffing or polishing machines and is designed particularly for use in polishing the reflecting surfaces of search-lights or head-lights.

My invention contemplates the combination of a die and plunger capable of relative movement to be brought together in a receptacle containing the proper polishing liquid and then causing a relative rotation between the die and plunger, it being, of course, understood that the reflector is in its operative position between the two.

Another object of the present invention resides in so arranging the structure to permit a circulation of the polishing liquid about the plunger to constantly supply the necessary polishing ingredients. In this manner, the reflector is polished as well as more properly shaped.

Other objects of my structure will appear from the following detailed description of the accompanying sheet of drawings, in which similar characters of reference designate corresponding parts, and in which:

Figure 1 is a view partially in central vertical section and partially in elevation showing my improved type of polishing machine, and,

Fig. 2 is a section taken through the receptacle as represented by line 2-2 of Fig. 1.

In these drawings, I have shown a cylindrical receptacle 1, which is designed to contain a die 2. This die may be made of any convenient material and I have found cement to be particularly good, inasmuch as it may be readily shaped. This die is provided with a central concavity as shown at 3 of a size to properly fit the reflector 4 and a liner member 5 which latter is permanently held in position therein. These lamp reflectors, particularly those used in connection with the headlights of motor vehicles, are provided with a central aperture in their rear, as is shown at 6 and I have accordingly provided the die and the lining member with a corresponding registering opening, this latter opening being in turn in communica-

tion with lateral passageways shown at 7 which open into the receptacle. Mounted in co-operative relation with the die is a plunger 8 which is shaped to correspondingly fit the interior of the reflector and may be made of material which will resist the action of the polishing medium. I have found lead to be particularly adaptable for this purpose.

The receptacle 1 is itself securely mounted upon a shaft 9 which shaft is slidably mounted within a bearing portion 10 of the base or supporting structure 11. In order that the die and plunger may be moved together into co-operative relation, I have extended the shaft 9 a considerable distance beneath the base 11 and have pivotally connected a link 12 at its lower end, as is shown at 13. The upper end of this link is pivotally connected, as shown at 14, to one arm of a bell crank 15, this latter being also pivotally mounted to the base member, as is shown at 16. The upstanding arm of this bell crank is provided with a rod 17 and this rod adjustably carries a counterweight 18 at its rear end, the counterweight itself being adjustable by means of the set screw shown at 19. In Fig. 1, the receptacle is shown in its inoperative position in full lines and in its operative position in dotted lines, the corresponding positions being indicated in similar lines for the remaining structure. Thus, when the rearwardly extending rod 17 carrying the counterweight 18 is grasped and lowered to the position shown in broken lines, the receptacle will be elevated to bring the head 8 into bearing engagement with the reflector located within the die 2. This counterweight is preferably adjusted to yieldingly hold the die and plunger in engagement to permit the flow of the polishing liquid, as will be presently described.

The base 11 is also provided with an upstanding standard 20, which carries two bearing portions 21 and 22. The bearing portion 21 serves to rotatably support the shaft 23 on to the lower end of which the plunger 8 is rigidly secured and on to the upper end of which the bevel gear 24 is secured. This latter gear is designed to mesh with a bevel pinion 25 rigidly secured to the drive shaft 26 by means of a set screw 27 and this shaft 26 itself is rotatably journaled in the bearing portion 22. Thus, after the plunger and die have been moved together, the relative rotation between the two caused by rotating the head 8 through its gear con-

nexion with the drive shaft, will cause the polishing action.

As is shown in Fig. 2, the reflector 4 is provided with a rim portion 28 which is 5 notched out at a plurality of points, as shown at 29. The liner member 5 is provided with a corresponding set of lugs 30 designed to seat themselves in these notched-out portions to thereby prevent the rotation 10 of the reflector during the polishing action. The operation of my machine is as follows: The receptacle 1 is filled to the desired level with the polishing material, such as emery dust and water. The reflector 4 is 15 then placed in its position upon the liner 5 so that the notched-out portions 29 engage the lugs 30 to prevent its rotation. The arm 17 is then grasped and moved to the position shown in dotted lines in Fig. 1, 20 whereby the plunger and head are brought into contacting engagement, but this engagement is slightly yielding. The rotation of the line shaft causes the rotation of the head 8 through the gear connection 24 and 25 and because of the speed at which the head 25 rotates, the water between the die and plunger will be correspondingly rotated and thrown laterally by the action of centrifugal force and this in turn causes a circulation 30 of this water through the passages 7 and the opening 6 in the bottom of the reflector. It follows, therefore, that the required supply of new emery to facilitate the polishing operation, is provided. I have found that 35 this emery has a tendency to adhere to the plunger 8 and at the completion of the polishing operation a considerable quantity has been deposited thereon. In order to compensate for this, the holding action between 40 the die and plunger has been made yielding by virtue of the counterweight 18 and thus, as the head 8 is built up, the receptacle and die will be automatically retracted.

From the foregoing description, it will 45 be apparent that I have provided a machine which is capable of mechanically polishing the reflecting surfaces of these reflectors and that this polishing is accomplished in such manner that all surfaces operated upon, 50 will present the same degree of brilliancy. Should there be a number of these machines arranged side by side to constitute a battery and further, should it be desired to stop the 55 operation of one of them the set screw 27 may be loosened from the gear 25 and this gear moved sidewise to an inoperative position. This will prevent the operation of this machine and permit the remainder to continue.

60 What I claim, is:

1. A polishing machine of the character described comprising a receptacle adapted to contain a polishing liquid, a die in said

receptacle, a plunger, means for relatively moving the die and plunger to bring them 65 together, and means for causing a relative rotation between said die and plunger when the two are together and in the liquid.

2. A polishing machine of the character described comprising a receptacle adapted 70 to contain a polishing liquid, a die in said receptacle, a plunger, means for relatively moving the die and plunger to bring them together, means for causing a relative rotation between said die and plunger when the 75 two are together, and means whereby a circulation of polishing liquid may be established between the die and plunger when they are together.

3. A polishing machine of the character 80 described comprising a receptacle adapted to contain a polishing liquid, a die in said receptacle, a plunger, means for relatively moving said die and plunger to bring them together and yieldingly hold them together, 85 and means for causing a relative rotation between said die and plunger when the two are together and in the liquid.

4. A polishing machine of the character described comprising a receptacle adapted to 90 contain a polishing liquid, a concave die therein having passages leading from the concavity into said receptacle, a plunger, means for relatively moving said die and plunger to bring them together, and means 95 for causing a relative rotation between said die and plunger when the two are together.

5. A polishing machine of the character described comprising a die, a plunger, means for relatively moving said die and plunger 100 to bring them together, means for causing a relative rotation between said die and plunger when they are together, and means whereby a circulation of polishing liquid 105 may be maintained between the die and plunger when they are together with the reflector between them.

6. A polishing machine of the character described comprising a die, a plunger, means for relatively moving said die and plunger 110 to bring them together, means for causing a relative rotation between said die and plunger when they are together, means whereby a circulation of polishing liquid may be maintained between the die and plunger 115 when they are together with a reflector between them, and means for yieldingly holding said die and plunger in said cooperative relation.

In testimony whereof I affix my signature 120 in presence of two witnesses.

LEO L. PFEIFER.
